UNITED STATES PATENT OFFICE.

CHARLES G. WIELAND, OF NEW YORK, N. Y.

SCREW-PROPELLER.

1,012,308.

Specification of Letters Patent. Patented Dec. 19, 1911.

Application filed September 5, 1911. Serial No. 647,574.

To all whom it may concern:

Be it known that I, CHARLES G. WIELAND, a subject of the German Emperor, and resident of the city of New York, in the county 5 of New York and State of New York, have invented certain new and useful Improvements in Screw-Propellers, of which the following is a specification.

The present invention relates to screw propellers adapted for use upon both aerial and marine vessels.

These propellers, as usually made, employ a plurality of blades which act upon the water or upon the air to propel the vessel. A 15 great loss of power is, however, occasioned by rotating them in water for the reason that a great deal of splashing takes place, and in the air because the blades, as heretofore constructed, are unable to grip the air, 20 as it were, or in other words thrust properly upon the air.

It is one of the objects of the present invention to obviate the defects of the propellers heretofore used, and to provide a 25 simple and effective propeller which will exert a pushing effect upon the water or air which is considerably larger at a given number of revolutions than that exerted by the propellers heretofore in use, whereby a 30 greater speed is obtained.

With these and other objects in view, which will more fully appear as the nature of the invention is better understood, the same consists in the combination, arrangement and construction of parts hereinafter fully described, pointed out in the appended claims and illustrated in the accompanying drawings, it being understood that many changes may be made in the size and proportion of the several parts and minor details 40 of construction without departing from the spirit or sacrificing any of the advantages of the invention.

A few of the many possible embodiments 45 of the invention are illustrated in the accompanying drawings, in which:—

Figure 1 is a front elevation of a propeller constructed in accordance with this invention; Fig. 2 is a side elevation thereof; 50 Fig. 3 is a section taken on line 3—3 of Fig. 1; Fig. 4 is a front elevation of a modified construction; Fig. 5 is a side elevation of this modification; Fig. 6 is a section taken on line 6—6 of Fig. 4; Fig. 7 is a similar 55 section taken through another modification;

Fig. 8 is a front elevation of a further modification of a propeller made in accordance with this invention; Fig. 9 is a side elevation of the same; and Fig. 10 is a section taken on line 10—10 of Fig. 8.

Referring now more particularly to Figs. 1 to 3, inclusive, the numeral 20 indicates a hub, having an opening 21 therethrough to receive the propeller-shaft. Projecting from the hub are two similar blades 22, 22, of a 60 size and pitch which may be varied according to the requirements. In the drawings the blades and the hub have been shown as a single casting, but it will be easily seen that the blades may be made separately and attached to the hub in any suitable manner. The propeller, as described thus far, is in all respects similar to those heretofore used.

With each blade is made integral a wall 23, which extends from the peripheral portion of the blade toward the hub 20. More particularly, the wall joins the peripheral edge 24 of the blade, is spaced apart from the blade, and extends toward the hub 20 through a distance which corresponds about 75 to one-half of the length of the blade, and merges then at 25 into the blade. The wall 23 runs throughout the width of the blade substantially parallel with the same, but inclines to some extent from the leading edge 80 26 of the blade toward the edge 27 which follows. The line 25 of the wall 23, which constitutes the line of contact between said wall and the blade, starts upon the leading edge 26 at a point which is considerably 85 nearer to the center of the hub 20 than its point on the following edge 27, whereby a conduit 28 is formed, which is bounded by the surface of the propeller and the inner surface of the wall 23, and which gradually 90 increases in cross section from the leading edge 26 toward the following edge 27, or in other words, the area of the conduit decreases gradually from its inlet 29 toward its outlet 30.

The operation of this propeller is as follows: When rotation is imparted to the same by the motor of an aerial vessel, an air current will be created by the blades and the outer surfaces of the walls 23, 23 in a direction 105 substantially parallel with the longitudinal axis of the propeller-shaft. At the same time air will enter at the leading edges the conduits 28, and be compressed to some extent as it passes through the gradually de- 110

creasing areas of said conduits, thereby increasing the thrust of the propeller blades upon the air. Owing to this increase of thrust, or increase of grip, as it were, of the 5 propeller blades upon the air, the speed of the vessel will be increased to a great extent.

The device shown in Figs. 4 to 6, inclusive, differs from the one hereinbefore described in that the conduits 28 are divided 10 by a plurality of substantially parallel partitions 31, 31 into a number of passages 32, 32, the inlets 33 of which are larger than the outlets 34 thereof. The operation of this device is in all respects similar to that 15 of the device shown in Figs. 1 to 3, inclusive, of the drawings, the only difference being that a plurality of air currents will be created by the passages 32, such air currents being parallel in direction.

20 In Fig. 7 of the drawings a modification of the propellers shown in Figs. 4 to 6, inclusive, is illustrated. The passages 32' of this propeller are provided with outlets 34', which direct the air passing through said 25 passages in a direction substantially parallel to the longitudinal axis of the propeller shaft for the reason that the walls 23 are curved forward at their edges which register with the following edges 27 of this 30 propeller, as clearly shown at 35. It is obvious that the air currents created by the passages of this propeller aid to a great extent the currents created by the blades of the same, since both sets of currents flow 35 in the same direction.

A further modification of the device is illustrated in Figs. 8 to 10, inclusive, in which the hub 36 is provided with the usual blades 37, 37, and upon the outer portion 40 of each blade is provided a pocket 38 extending from the periphery 39 of each blade toward the hub through a distance which corresponds to about one-half of the length 45 of the blade. The pockets are open at the leading edges 40 of the blades, and provided with a plurality of substantially parallel partitions 41, 41, dividing the same into a number of passages 42' which are gradually decreasing from the leading edges 50 40 toward the following edges 42 of the propeller. Each passage is provided near to the following edge 42 with an outlet 43 which is arranged in a plane substantially parallel to the blade of the propeller.

55 The operation of this device is as follows: In rotating the propeller, a current of air or water, as the case may be, will be created by the blades and the outer surfaces of the pockets 38, of course, in a direction substantially 60 parallel to the longitudinal axis of the propeller shaft, not taken into consideration the splashing action of the propeller. The air which enters the passages 42' is highly compressed as it passes toward 65 the outlets 43, through which it is forced

out by the rotary action of the propeller in the direction of the longitudinal axis of the shaft of the latter. The reaction of the air currents, passing out from the outlets 43, increases the speed of the vessel to a great 70 extent. The same conditions are true when the propeller is used upon a marine vessel with the exception that the water passing through the passages 42' will not be compressed, but its speed increased owing to the 75 decreasing cross section of the passages toward their outlets. The result will, of course, be the same as the one described in connection with the aerial vessel.

What I claim is:—

1. A propeller comprising a hub, and a plurality of blades projecting therefrom provided with conduits running from their leading edges toward their following edges substantially parallel with the faces of said blades and gradually decreasing in cross section toward their following edges. 80

2. A propeller comprising a hub, and a plurality of blades projecting therefrom provided with conduits running from their leading edges to their following edges substantially parallel with the faces of said blades and gradually decreasing in cross section toward their following edges. 90

3. A propeller comprising a hub, and a plurality of blades projecting therefrom provided with conduits running from their leading edges toward their following edges substantially parallel with the faces of said blades and being provided with outlets 100 adapted to discharge the air passing through said conduits in a direction substantially parallel with the longitudinal axis of said hub. 95

4. A propeller comprising a hub, and a plurality of blades projecting therefrom provided with conduits running from their leading edges toward their following edges substantially parallel with the faces of said blades and gradually decreasing in cross section toward their following edges, said conduits being provided with outlets adapted to discharge the air passing therethrough in a direction substantially parallel with the longitudinal axis of said hub. 110

5. A propeller comprising a hub, and a plurality of blades projecting therefrom provided with conduits running from their leading edges to their following edges substantially parallel with the faces of said blades and being provided with outlets adapted to discharge the air passing through said outlets in a direction substantially parallel with the longitudinal axis of said hub. 115

6. A propeller comprising a hub, and a plurality of blades projecting therefrom provided with conduits running from their leading edges to their following edges substantially parallel with the faces of said 120 blades and gradually decreasing in cross section toward their following edges, said conduits being provided with outlets adapted to discharge the air passing through said outlets in a direction substantially parallel with the longitudinal axis of said hub. 125

130

blades and gradually decreasing in cross section toward their following edges, said conduits being provided with outlets adapted to discharge the air passing therethrough in a direction substantially parallel with the longitudinal axis of said hub.

Signed at New York, in the county of

New York and State of New York, this 2nd day of September, A. D. 1911.

CHARLES G. WIELAND.
